UNITED STATES PATENT OFFICE.

DAVID ROSENBACH, OF CHICAGO, ILLINOIS, ASSIGNOR TO ILLINOIS AUTOMOBILE CLUB, OF CHICAGO, ILLINOIS, A CORPORATION OF ILLINOIS.

DESIGN FOR AN EMBLEMATIC ARTICLE OF MANUFACTURE.

56,239.

Specification for Design.

Patented Aug. 31, 1920.

Application filed March 1, 1920. Serial No. 362,559. Term of patent 14 years.

To all whom it may concern:

Be it known that I, DAVID ROSENBACH, a citizen of the United States, residing at Chicago, in the county of Cook and State of Illinois, have invented a new, original, and ornamental Design for an Emblematic Article of Manufacture, of which the following is a specification, reference being had to the accompanying drawing, forming a part thereof.

The figure is a face view of a name plate or similar article of manufacture.

I claim:

The ornamental design for an emblematic article of manufacture as shown.

DAVID ROSENBACH.
